UNITED STATES PATENT OFFICE.

ROMONDO D. MARKHAM, OF CHICAGO, ILLINOIS, ASSIGNEE TO AUTO LOCK CO., OF CHICAGO, ILLINOIS, A CORPORATION OF ILLINOIS.

LOCK FOR MOTOR-STARTING CRANKS.

958,815.

Specification of Letters Patent. Patented May 24, 1910.

Application filed March 13, 1909. Serial No. 483,120.

To all whom it may concern:

Be it known that I, ROMONDO D. MARKHAM, a citizen of the United States, residing at Chicago, in the county of Cook and State 5 of Illinois, have invented certain new and useful Improvements in Locks for Motor-Starting Cranks, of which the following is a full, clear, and exact specification.

This invention relates generally to means 10 for locking the starting cranks of motors, but has more especial reference to a lock for preventing the motors of automobiles and the like from being started by unauthorized persons.

The subject matter of the present invention is closely related to that of my former application, Serial No. 405,661, filed December 9, 1907.

In the construction of automobiles and the like, it is customary to provide the starting element or crank of a machine with a clutch so that by pushing the starting crank longitudinally it may be caused to come into rotative or clutching engagement with the engine shaft whereby the engine may be turned over one or more times until it starts, whereupon the clutch will be automatically forced out of engagement, returning the starting crank to its original position.

My invention has for its primary object to provide means whereby the starting crank or element may be locked against moving into rotative engagement with the shaft of the motor or other rotary part by which the motor may be started.

With a view to the attainment of these ends and the accomplishment of certain other objects which will hereinafter appear, the invention consists in the features of 40 novelty which will now be described with reference to the accompanying drawings and more particularly pointed out in the claims.

In the said drawings, Figure 1 is a vertical longitudinal sectional view of a guide or support for the starting element or crank, showing a portion of the latter in section and also illustrating it in its engaged position. Fig. 2 is a detail sectional view on the line 2--2 of Fig. 1. Fig. 3 is a front elevation 50 of the starting crank. Fig. 4 is a perspective view of a sleeve hereinafter described. Fig. 5 is a perspective view of a part of the lock case. Fig. 6 is a perspective view of the lock removed. Fig. 7 is a horizontal section on the line 7--7 of Fig. 1.

Ordinarily, and especially in automobile construction, it is customary to journal the starting crank or element of the machine in a guide or support 1, in which the stem 2 of the crank 3 slides and rotates. The stem 2 is arranged in axial alinement with the engine shaft 4, and the latter is provided with some suitable clutch member, such as one or more pins 5 projecting radially therefrom, while the stem 2 is equipped with a companion clutch member in the form of a notched collar 6 which fits over the end of the shaft 4 and engages the pin 5 when the stem 2 is forced toward the shaft and rotated by means of the crank 3 in one direction. 60 When the engine or motor starts or commences to run under its own power, the clutch members 5, 6 automatically release, causing the stem 2 to move outwardly away from the shaft 4, where it is customarily held by the yielding action of a spring suitably arranged for imparting a normal outward tendency to the stem and preventing the clutch members from accidentally coming into engagement. In this example of 65 the invention the spring is shown at 7 in the form of the coil spring surrounding the stem 2 at its outer end. The spring bears at one end against the head or body 3^a of the crank, while at its other end it bears against 70 a shoulder 8 formed on the inner end of a sleeve 9 which surrounds the stem 2 and incases the spring 7. By this means it will be seen that the sleeve 9 is normally pressed against the guide or support 1, which being 75 a fixture, enables the spring to force the stem 2 outward in a direction away from the shaft 4 and consequently the stem cannot be forced inward for bringing it into rotative engagement with the shaft unless the 80 stem be capable of moving relatively to the sleeve 9. In order that this relative movement may be prevented, I provide suitable means of locking the starting element and the sleeve 9 together. To this end I provide 85 the sleeve with a notch 10 and upon the head 3^a I mount any suitable lock having a bolt or latch 11, adapted to swing downwardly 100 into engagement with the notch 10, thereby holding the head 3^a against inward movement with relation to the sleeve 9 and as the sleeve 9 is permanently in firm engagement with the guide 1, it necessarily follows that the stem 2 cannot be forced into rotative 105 engagement with the shaft 4 until the latch 110

or bolt 11 is again withdrawn from the notch 10, although the crank and stem 2 will be free to rotate together with the sleeve 9, the sleeve 9 being held against independent 5 rotation by a pin 12, secured in the head 3* and engaging in a slot 13 formed longitudinally in the sleeve 9. If desired the stem 2 may be locked in its position of rotative engagement with the shaft 4 by providing the 10 sleeve 9 with an additional notch 14 for the engagement of the latch 11 when the starting element is forced inwardly, placing the spring 7 under compression.

In this exemplification of the invention 15 the head 3* of the starting element or crank is formed integrally with the crank 3 and the stem 2, and surrounds the sleeve 9 and is also formed with a lock housing 15, which holds and incases the lock for controlling 20 the bolt or latch 11. This lock may be an ordinary lock of commerce, such as shown in Fig. 6, capable of being inserted from the front side of the housing 15, and held in place therein in any appropriate way, the 25 back of the housing being closed by a plate 16 carrying a block or stop 17 for limiting the movement of the latch or bolt 11 in one direction, but any other suitable form of lock and arrangement and construction of 30 housing and connective parts might answer the purpose. If desired, the key-hole may be protected by a shield or cover 18 recessed in the front of the housing 15, and having a stem or shank 19 pivoted on the pin 20 and provided with a flat shoulder 21 against 35 which press a spring pressed plunger 22 located in a socket 23 in the body 3* and serving to keep the cover or shield 18 closed.

In order that my invention may be understood by those skilled in the art, the details of an exemplification thereof have been thus specifically described, but

What I claim is:

1. In a device for the purpose described, a 40 lock comprising a sleeve mounted upon a crank shaft between the crank and the frame of the machine and suitable means for positively locking the said sleeve on said shaft to prevent longitudinal movement thereof.

2. In a device for the purpose described, the combination of a motor shaft, a starting element having means for rotative engagement with said shaft, movable longitudinally thereof into and out of its engaging position, a guide for directing the starting element into and out of engaging position, and means for locking the starting element against longitudinal movement toward the 55 motor shaft while permitting its rotary movement.

3. In a device for the purpose described, the combination of a motor shaft, a starting element having means for rotative engagement with said shaft, movable longitudinally

thereof into and out of its engaging position, a guide for directing the starting element into and out of engaging position, a member on the starting element incapable of passing said guide and with reference 70 to which member the starting element is movable toward and from said shaft, and means for locking the said member and element together.

4. In a device for the purpose described, 75 the combination of a motor shaft, a starting element having means for rotative engagement with said shaft, movable longitudinally thereof into and out of its engaging position, a movable sleeve through which 80 the starting element is longitudinally movable, an abutment or stop for said sleeve, and means for locking the sleeve and starting element against relative longitudinal movement.

5. In a device for the purpose described, 85 the combination of a motor shaft, a starting element having means for rotative engagement with said shaft, movable longitudinally thereof into and out of its engaging 90 position, said starting element embodying a stem, a shouldered sleeve surrounding said stem and spaced therefrom, a spring surrounding said stem within said sleeve and bearing between the shoulder thereof and 95 the starting element for tending to force the sleeve and starting element apart, an abutment for said sleeve for limiting its movement toward said shaft, and means for locking the starting element and sleeve 100 against relative longitudinal movement.

6. In a device for the purpose described, 105 the combination of a motor shaft, a starting element having means for rotative engagement with said shaft, movable longitudinally thereof into and out of its engaging position, said starting element embodying a stem, a shouldered sleeve surrounding said 110 stem and spaced therefrom, a spring surrounding said stem within said sleeve and bearing between the shoulder thereof and 115 the starting element for tending to force the sleeve and starting element apart, an abutment for said sleeve for limiting its movement toward said shaft, and means for locking the starting element and sleeve 120 against relative longitudinal movement, said starting element also embodying a head or body portion incasing the sleeve and said locking means.

7. In a device for the purpose described, 125 the combination of a motor shaft, a starting element having means for rotative engagement with said shaft, movable longitudinally thereof into and out of its engaging position, 130 said starting element embodying a stem, a movable sleeve surrounding said stem, an abutment or stop for limiting the movement of the sleeve toward the shaft, said starting element also embodying a body portion en-

compassing the sleeve, and means for locking the sleeve and starting element against relative longitudinal movement.

8. In a device for the purpose described, the combination with a motor shaft of a starting element movable longitudinally into and out of rotative engagement with said shaft, a stationary guide for said starting element, and means for locking said starting element against longitudinal movement and in different positions with respect to said guide, said locking means being mounted on the starting element.

9. In a device for the purpose described, the combination with a motor shaft of a starting element movable longitudinally into and out of rotative engagement with said shaft, a stationary guide for said starting element, and means for locking said starting element against longitudinal movement relative to the guide, said locking means being adjustable relatively to the starting element into and out of locking position.

10. In a device for the purpose described, the combination with a motor shaft of a starting element reciprocable into and out of rotative engagement with said shaft, a guide for said starting element, means for locking

said starting element against reciprocating movement relative to said guide, said locking means comprising a sleeve reciprocable on said starting element, said sleeve being provided with axially spaced notches therein, and a locking bolt mounted on said starting element and held against axial movement relative thereto, said bolt being movable into and out of engagement with the recesses in said sleeve.

11. In a device for the purpose described, the combination with a motor shaft, of a rotatable starting element movable longitudinally into and out of rotatable engagement with the motor shaft, a guide for said starting element, and means interengaging between the starting element and the guide for rotatably holding said starting element against longitudinal movement.

In testimony whereof I have signed my name to this specification, in the presence of two subscribing witnesses, on this 11th day of March A. D. 1909.

ROMONDO D. MARKHAM.
